(57) **CLAIM**

The ornamental design for a filament spool container, as shown and described.

DESCRIPTION

Reference is hereby made to co-filed U.S. patent application Ser. No. 12/255,808, entitled “Filament Spool”; co-filed U.S. patent application Ser. No. 12/255,811, entitled “Filament Guided Mechanism for Filament Spool Container”; and co-filed U.S. patent application Ser. No. 29/326,639, entitled “Filament Spool”.

FIG. 1 is a top front perspective view of a first embodiment of a filament spool container, embodying our new design;

FIG. 2 is a bottom front perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is a top front perspective view of a second embodiment of a filament spool container, embodying our new design;

FIG. 10 is a bottom front perspective view thereof;

FIG. 11 is a top view thereof;

FIG. 12 is a bottom view thereof;

FIG. 13 is a front view thereof;

FIG. 14 is a rear view thereof;

FIG. 15 is a left side view thereof; and,

FIG. 16 is a right side view thereof.

Features illustrated with dashed lines are not considered features of the invention being claimed, but rather illustrate an exemplary environment for the claimed features illustrated with solid lines.
